STOKER

Calvert C. Wright, State College, Pa., assignor to
 Pennsylvania Bituminous Coal Research, Inc.,
 Altoona, Pa., a corporation of Pennsylvania

Application November 10, 1943, Serial No. 509,651

2 Claims. (Cl. 110—45)

This invention relates to stokers, more particularly to underfeed stokers which operate on the principle of partial oxidation of coal prior to its undergoing active combustion.

Underfeed stokers as ordinarily constructed do not operate satisfactorily with strongly coking coals, such as the Pennsylvania coking coals. That is, when it is attempted to burn a strongly coking coal in an underfeed stoker of customary construction there is a strong tendency for unburned coke to be formed and to accumulate and build up above the retort in a generally columnar form known as a coke tree. Coke trees burn primarily at the base, and the presence of a coke tree results in unsatisfactory combustion, especially when the demand on the heating unit is not great, it slows down the response of the furnace to demand for heat and causes over-shooting of thermostatic control, and it makes it difficult to maintain low hold-fire rates without danger of the fire going out. In fact, coke tree formation may become so extensive as actually to extinguish the fire or to push open the furnace door.

A method of and apparatus for avoiding the formation of coke trees from coking coals by mildly oxidizing the coal before active combustion begins are described and claimed in an application filed by Theodore S. Spicer and Calvert C. Wright on April 15, 1941, Serial No. 388,626, and owned by the present assignee. More in detail, as the coal moves upwardly into and through the lower end of the retort of the stoker it is heated by conduction of heat downwardly from the actively burning coal, and in that portion of the column of coal in which the coal is heated but is not yet plastic, i. e., where coking has not begun, the coal is oxidized to an extent such as to reduce but not destroy its coking power. This oxidation is chiefly a surface phenomenon but does not involve active combustion. This is accomplished by introducing an oxidizing agent, most suitably air or an air-stream mixture into the coal at a point or in a region such that it comes into intimate contact with the heated but non-plastic coal. For brevity this procedure is referred to as a pre-oxidation method of operating a stoker, or as the preoxidation principle.

Extended experience has demonstrated amply that the preoxidation method easily and satisfactorily represses coke tree formation provided certain critical details are observed. In the first place, the coal must be mixed intimately with the oxidizing agent as it moves upwardly through the preoxidation zone. Second, as the coal is mixed

and elevated any substantial segregation must be avoided; i. e., it is necessary to maintain substantial uniformity of coal size distribution across the section while mixing it intimately with the oxidizing agent. These features result in subjecting all of the coal uniformly to the action of the pre-oxidizing air or other oxidizing agent, but observation of them is necessary because it has been found that coke tree suppression is not attained satisfactorily if the coal is not thoroughly mixed with the air or if the air distribution is not uniform due to channeling or segregation of the coal into regions containing largely fines and regions containing largely coarse particles. And as indicated above, the coal must be heated but not sufficiently to render it plastic, and enough oxidizing agent must be supplied to produce the desired oxidation before coking of the coal begins.

Although the necessary elevation and mixing of the coal without segregation in the preoxidation zone may be accomplished satisfactorily in various ways, the simplest and most effective means for doing so is a vertical screw. Likewise, although the oxidizing agent might be introduced into the coal at any point prior to the preoxidation zone, it is preferred to supply the oxidizing agent through a supplementary, or preoxidizing, tuyère situated below the regular or active combustion tuyères at a distance such that the agent enters the coal substantially at the lower end of the preoxidation zone.

It has been found in actual practice that in the operation of such a stoker there is a tendency for coal to enter the supplementary tuyère, even to the extent of closing the tuyère opening. This is serious because it decreases the amount of air supplied by the supplementary tuyère to the coal and coke trees result because the coal is not oxidized sufficiently. Moreover, continued operation may completely fill the tuyère openings and by forcing coal through the tuyère cause the wind box to be filled with riddlings, which is objectionable.

A copending application filed by Speer W. Guthrie on November 5, 1943, Serial No. 509,071, also owned by the present assignee, discloses and claims means for alleviating the foregoing difficulty. According to that invention the supplementary tuyère is constructed to have a continuously unobstructed opening for rotation therein of a scraper member which acts to clear coal from the opening. The embodiment shown in the application includes a vertical screw for elevating the coal, and a hooked, or claw-like, scraper member is connected to the edge of the screw blade

so as to move in the tuyère opening when the screw is in operation. As far as I am aware the construction described was the first means to be provided which afforded any degree of relief from the aforementioned difficulty of coal riddlings in the supplementary tuyère. Experience with it has shown that it acts to sweep riddlings from the tuyère, thus permitting the tuyère to serve its intended function efficiently, but that equally it has a tendency to push a portion of the riddlings into the wind box. While not an insuperable obstacle, that tendency is undesirable because it necessitates periodic cleaning of the wind box and, particularly with domestic stokers, stoker builders seek to eliminate such upkeep requirements as far as possible.

The major object of this invention is to provide a stoker constructed and operated in accordance with the preoxidation principle with simple and inexpensive scraper means for automatically 20 keeping the supplementary, or preoxidation, tuyère free from coal, and which does so more effectively than is accomplished by the means proposed heretofore.

Other objects will appear from the following 25 description.

The invention will be described with reference to the accompanying drawing in which Fig. 1 is a vertical sectional view through the significant part of a preoxidation-type stoker constructed in accordance with one embodiment of the present invention; and Fig. 2 a horizontal section taken on line II—II, Fig. 1.

I have discovered, and it is upon this that the present invention is predicated, that the tendency of a scraper carried by the screw flight, or blade, to push coal from the supplementary tuyère into the wind box can be repressed, and the object of the invention attained, by mounting the scraper so that it lags the horizontal component of the upward thrusting action of the elevating screw. In accordance with the invention this is accomplished by connecting the scraper to the shaft of the vertical screw at a position such that the elevating action of the screw leads the action of the scraper.

Having reference now to the drawing, there is shown a preoxidation type of stoker comprising a retort 1 of conventional form provided with one or more main combustion tuyères which form the active combustion zone in the manner customary in the art. The embodiment shown includes two such tuyères, 2 and 3, Fig. 1. The retort is surrounded by a wind box 4 supplied with air or other oxidizing agent from a main air duct 5 in any suitable way, as by a motor driven blower. Coal is introduced to the retort by a horizontal screw 6 operating in a conduit 7. The blower which supplies air to main duct 5 and the screw conveyor 6 are operated in any suitable manner; such drive means form no part of this invention and because they are well understood in the art they do not require illustration or further description.

Coal is delivered by screw conveyor 6 to the bottom of the retort where it is picked up and moved upwardly by a screw flight 8 mounted on a vertical shaft 8a operated by a gear 9 and a pinion 10 which may suitably be driven by the motor which operates screw 6. During the on periods of the stoker screw conveyor 6 moves the coal progressively and continuously upwardly through the retort into the active combustion zone and in so doing the coal is mixed without segregation of particles or pieces of varying sizes.

Disposed in wind box 4 is a partition 11 which divides it into an upper air chamber 12 through which air is supplied to the main combustion tuyères 2 and 3, and a lower air chamber 13 through which air is supplied to the preoxidation tuyère 14. Chambers 12 and 13 act as conduits for supplying air to the main and supplementary tuyères, respectively. Mounted at the juncture of wind box 4 and the main air duct for pivotal movement about the end of partition 11 is a butterfly valve 15. By moving it appropriately, as indicated by the broken line positions, Fig. 1, the air supplied through duct 5 may be apportioned in any desired manner between the upper and lower air chambers 12 and 13. Thus, all of the air may be passed to the upper tuyères 2 and 3, or all of it may be passed to the preoxidation tuyère 14. In ordinary practice, however, valve 15 will be adjusted to supply an amount of air to the preoxidation tuyère 14 which effects preoxidation sufficient to prevent coke tree formation, and air necessary for combustion is passed directly to the active combustion zone through upper air chamber 12 and tuyères 2 and 3. A smoke-back opening 16 may be provided as shown in Fig. 1 for the usual purpose of preventing back pressure at this point.

The upper, or active combustion, tuyères 2 and 3 are, as will be observed from Fig. 1, of the usual sectional construction which forms a series of spaced openings between webs 2a and 3a. The preoxidation tuyère 14 has, however, a continuously unobstructed opening, as shown in the drawing, to permit a scraper member to enter and to pass completely around the tuyère opening to sweep from it any pieces of coal that may find their way into it.

In the embodiment shown the scraper comprises a scraper blade 17 carried by an arm 18 which is seated in a bore in the vertical screw conveyor shaft 8 and is held rigidly in place in any suitable way, as by a set screw 19.

The present invention is predicated, as indicated above, upon a particular mounting of the scraper 17. To this end the arm which carries the scraper is connected to the vertical shaft 8a at a level such that the scraper blade will move through the opening of tuyère 14, and it is so positioned with respect to screw flight 8 as to be offset with respect thereto, i. e., to lag the horizontal component of its upward thrusting action in the plane of the tuyère opening, suitably by about one-fourth turn. Most suitably arm 18 is connected to shaft 8a at a point not far below the flight and the flight is operated so that the area just above and below the arm is open. The scraper then acts immediately after the screw has exerted its maximum tendency to push coal into the opening of the preoxidation tuyère.

The operation of a stoker constructed in accordance with the drawing will be understood from what has been said above. Briefly, during the on periods of the stoker coal from a hopper or bin, not shown, passes through conduit 7 to the bottom of the retort and is there picked up by screw conveyor 6 and moved upwardly toward the active combustion zone. Air for preoxidation enters tuyère 14, which is situated at a level such that the temperature of the coal is sufficient for initiation of the desired preoxidation but insufficient to make it plastic. Under the combined action of mixing by conveyor 6, with avoidance of segregation of fines, and of the air introduced through tuyère 14, the coal is sufficiently oxidized, by the time it reaches the plastic zone, which lies

at or immediately above the upper end of conveyor 8, that coke trees do not form when the coal burns in the active combustion zone, i. e., in the region of tuyères 2 and 3.

Meanwhile, rotation of screw flight 8 continuously moves scraper 11 through the opening of tuyère 14. In consequence of the positioning of this scraper and the action of its leading edge, it acts continuously to sweep riddlings from tuyère 14.

Various modifications are, of course, permissible. For example, the leading edge of the scraper member may be shaped in other ways than shown in the drawing, or a plurality of scrapers of the type and mounted as described might be provided at spaced intervals.

According to the provisions of the patent statutes, I have explained the construction and mode of operation of my invention and have illustrated and described what I now consider to represent its best embodiment. However, I desire to have it understood that, within the scope of the appended claims, the invention may be practiced otherwise than as specifically illustrated and described.

I claim:

1. An underfeed stoker comprising the combination of a substantially vertical retort provided with a main combustion tuyère at the upper portion where active combustion occurs, means for supplying coal to the lower end of said retort, a vertical shaft screw conveyor disposed in said retort for moving coal upwardly in the retort while mixing it thoroughly and maintaining substantial uniformity of size distribution, the upper

end of said screw being disposed below the plane of said tuyère, a supplementary tuyère having a continuously unobstructed opening disposed in the retort wall below said main combustion tuyère for supplying an oxidizing agent to the coal engaged by said screw in a region where the coal is heated but not plastic, conduits for supplying said oxidizing agent to the said tuyères, and a scraper member extending into said supplementary tuyère opening and connected to the shaft of said screw conveyor to lag the horizontal component of the upward thrust of the screw in the plane of the supplementary tuyère opening.

2. An underfeed stoker comprising the combination of a substantially vertical retort provided with a main combustion tuyère at the upper portion where active combustion occurs, means for supplying coal to the lower end of said retort, a vertical shaft screw conveyor disposed in said retort for moving coal upwardly in the retort while mixing it thoroughly and maintaining substantial uniformity of size distribution, the upper end of said screw being disposed below the plane of said tuyère, a supplementary tuyère having a continuously unobstructed opening disposed in the retort wall below said main combustion tuyère for supplying air to the coal engaged by said screw conveyor means in a region where the coal is heated but not plastic, conduits for supplying air to the said tuyères, and a scraper member extending into said supplementary tuyère opening and connected to the shaft of said conveyor between adjacent turns of the flight.

at or immediately above the upper end of conveyor 8, that coke trees do not form when the coal burns in the active combustion zone, i. e., in the region of tuyères 2 and 3.

Meanwhile, rotation of screw flight 8 continuously moves scraper 11 through the opening of tuyère 14. In consequence of the positioning of this scraper and the action of its leading edge, it acts continuously to sweep riddlings from tuyère 14.

Various modifications are, of course, permissible. For example, the leading edge of the scraper member may be shaped in other ways than shown in the drawing, or a plurality of scrapers of the type and mounted as described might be provided at spaced intervals.

According to the provisions of the patent statutes, I have explained the construction and mode of operation of my invention and have illustrated and described what I now consider to represent its best embodiment. However, I desire to have it understood that, within the scope of the appended claims, the invention may be practiced otherwise than as specifically illustrated and described.

I claim:

1. An underfeed stoker comprising the combination of a substantially vertical retort provided with a main combustion tuyère at the upper portion where active combustion occurs, means for supplying coal to the lower end of said retort, a vertical shaft screw conveyor disposed in said retort for moving coal upwardly in the retort while mixing it thoroughly and maintaining substantial uniformity of size distribution, the upper

end of said screw being disposed below the plane of said tuyère, a supplementary tuyère having a continuously unobstructed opening disposed in the retort wall below said main combustion tuyère for supplying an oxidizing agent to the coal engaged by said screw in a region where the coal is heated but not plastic, conduits for supplying said oxidizing agent to the said tuyères, and a scraper member extending into said supplementary tuyère opening and connected to the shaft of said screw conveyor to lag the horizontal component of the upward thrust of the screw in the plane of the supplementary tuyère opening.

2. An underfeed stoker comprising the combination of a substantially vertical retort provided with a main combustion tuyère at the upper portion where active combustion occurs, means for supplying coal to the lower end of said retort, a vertical shaft screw conveyor disposed in said retort for moving coal upwardly in the retort while mixing it thoroughly and maintaining substantial uniformity of size distribution, the upper end of said screw being disposed below the plane of said tuyère, a supplementary tuyère having a continuously unobstructed opening disposed in the retort wall below said main combustion tuyère for supplying air to the coal engaged by said screw conveyor means in a region where the coal is heated but not plastic, conduits for supplying air to the said tuyères, and a scraper member extending into said supplementary tuyère opening and connected to the shaft of said conveyor between adjacent turns of the flight.
